UNITED STATES PATENT OFFICE.

PETER NELS MADSEN, OF SOUTH CHICAGO, ILLINOIS, ASSIGNOR OF ONE-HALF TO LEO LA REAU, OF CHICAGO, ILLINOIS.

RAILWAY-RAIL.

1,079,054.

Specification of Letters Patent.

Patented Nov. 18, 1913.

Application filed April 17, 1913. Serial No. 761,658.

To all whom it may concern:

Be it known that I, PETER N. MADSEN, a citizen of the United States, and a resident of the city of South Chicago, county of 5 Cook, and State of Illinois, have invented certain new and useful Improvements in Railway-Rails, of which the following is a specification.

My invention relates to railway rails and 10 mountings therefor and the object of this improvement is to provide a railway rail and tie-plate arranged to hold a rail and prevent its turning thereon.

Other objects will appear hereinafter.

15 The invention consists in the combinations and arrangements of parts hereinafter described and claimed.

The invention will be best understood by reference to the accompanying drawing 20 forming a part of this specification, and in which—

Figure 1 is a view, in perspective, of a portion of a railway rail and tie plate embodying my invention, and Fig. 2 is a trans- 25 verse section of the same.

The preferred form of construction as illustrated in the drawing comprises a railway rail having the ordinary head portion 3 and shank 4. The flanges 5 and 6 of the 30 rail are provided one thicker than the other and forming a beveled under surface of the rail. The lateral edges of the base flanges 5 and 6 are parallel and vertically straight.

A tie-plate 7 is provided with a groove 35 corresponding to the cross-section of the flanges of the railway rail and of such a size and shape as will fit the flanges of the rail and prevent its turning thereon. Perforations are provided in the tie-plate 7 for conventional spikes 8 to prevent the rail from 40 being raised vertically out of the groove in said tie-plate. The tie-plate is also provided with points 9 on its under side to prevent creeping of the tie-plate.

The railway rail and tie-plate as described 45 herein is especially adapted for use on curves and where there is great side strain on the rail. The groove in tie-plate 7 is of such a size as to receive the flanges 5 and 6 of the rail substantially as indicated and in 50 a manner to prevent the rail from turning on the tie-plate. The rail and tie-plate are designed to be set so that the greatest side strain will be applied in the direction of arrow 10 indicated in Fig. 2. 55

While I have illustrated and described the preferred form of construction for carrying my invention into effect, this is capable of variation and modification without departing from the spirit of the invention. 60 I, therefore, do not wish to be limited to the precise details of construction set forth, but desire to avail myself of such variations and modifications as come within the scope of the appended claim. 65

Having described my invention what I claim as new and desire to secure by Letters Patent is:

In combination, a railway rail having base flanges with vertically straight lateral edges, 70 the lateral edge of one flange being considerably thicker than the lateral edge of the other flange and the under side of the rail being inclined downward toward the thicker edge of such rail; and a tie plate having a 75 groove therein snugly fitting the flanges on said rail and the inclined under side of said rail, substantially as described.

In testimony whereof I have signed my name to this specification in the presence 80 of two subscribing witnesses.

PETER NELS MADSEN.
